UNITED STATES PATENT OFFICE.

LESTER J. CARLETON, OF MANCHESTER, NEW HAMPSHIRE.

GOLFING ACCESSORY.

Application filed March 22, 1928. Serial No. 263,746.

This invention relates to golfing accessories, and comprehends a wiping device which is particularly designed as a means for effecting the removal of moisture, sand, mud 5 or other foreign substances from the handles of golf clubs.

The invention broadly contemplates a device of this nature which effectually functions to clean the club handle and free the 10 same of moisture, which devices may be installed at the various tees, in the club house or at predetermined points on the links or which devices may be portable and carried as a part of a golfer's equipment.

More specifically, the invention embodies 15 an accessory which includes one or more annular contractile wiper elements through which the club handle is axially passed or which device is axially moved over the club 20 handle, the inner periphery of the element being normally of a lesser diameter than the club handle to function in the manner of a squeegee to displace or remove moisture or 25 other substances which adhere to the surface of the handle.

Other objects of the invention reside in the 30 simplicity of construction and mode of use of the device, the economy with which the same may be produced and the general efficiency derived therefrom.

With the above recited and other objects in 35 view, reference is had to the following description and accompanying drawings, in which there is exhibited one example or embodiment 40 of the invention, while the claims define the actual scope of the same.

In the drawings—

Figure 1 is a perspective view of the device 45 secured to a support.

Figure 2 is a longitudinal sectional view 50 therethrough.

Figure 3 is a perspective view of one of the 55 wiping units removed from its housing.

Figure 4 is a transverse sectional view 60 through the unit taken approximately on the line 4—4 of Figure 5.

Figure 5 is a longitudinal sectional view 65 through the wiping unit illustrating a club handle operatively associated therewith.

Figure 6 is a sectional perspective view 70 illustrating as a modification a portable form of the device.

Figure 7 is a transverse sectional view 75 taken approximately on the line 7—7 of Figure 1.

In the form of the invention illustrated in

Figures 1 and 2 where the device is attached to a support such as a tee box, a suitable housing 1 is provided for protecting the wiper elements or units from the elements, and preferably this housing is of substantially tubular formation attached in any suitable manner such as by clamps 2 to its support. The housing as illustrated consists of a pair of mating semi-tubular sections 3 and 4, each 60 being respectively provided at one edge with longitudinally spaced inwardly offset lugs overlapping the edge of the other section and receiving therethrough suitable fastening elements such as the bolts 6 which detachably 65 retain the sections in mated assembled relation. The uppermost section 4 is formed with portions 4^a extending beyond the ends of the lower section 3 to constitute hoods for protecting the housing against the entrance of rain, 70 snow or sleet. The lower section 3 is formed with longitudinally spaced drain apertures 7 to allow for gravitational discharge of 75 water from the casing and to further assist in the circulation of air therethrough for drying the interior thereof and the wiping elements or units which are moistened thereby.

The units or elements 10 which constitute 80 one of the principal features of the present invention include essentially an annulus 11 of flexible material having a contractile inner 85 peripheral edge 12 which is normally of a diameter less than the diameter of the club handle H so as to function as a squeegee for 90 effectually contacting with the periphery of said club handle when the same is inserted and axially moved through the element or unit 95 10. The element or unit 10 preferably consists of a hollow cylindrical substantially rigid member 13 covered on its inner and outer faces by a sheath composed of strips of 100 flexible material 14 and 15, such as chamois. The strips are of greater length than the length of the cylindrical sections and the protruding edges which extend beyond the ends 105 of the member 13 are joined by a line of stitching 16 adjacent the opposite end edges of the member 13. The protruding edges are then directed inwardly and gathered by a line of stitching 17 which forms a bight presenting the inner annular edge 12. Where a non- 110 elastic material such as chamois is used, an annular circumferentially contractile element 18 is arranged within the bight formed by the line of stitching 17 for normally effecting circumferential contraction of the edge 12. In practice, the elements or units 10 are disposed

within the seats 8 thereby presenting a battery of wiper members within the housing 1. When during the progress of the game the handles of the clubs become moisture laden or sand, dirt or other foreign substances collect thereon, the golfer inserts the handle through the end of the housing and moves the same axially back and forth through the elements or units 10 to free the surface of the handle of moisture, sand, mud or other foreign matter so as to dry and remove said substances therefrom.

In Figure 6, there is illustrated as a modification of the invention a portable wiping device in which the elements or units 10^a are disposed within the seats 8^a of the cylindrical casing 1^a. In this form, the construction of the units or elements 10^a is identical with that previously described. In this instance, the device may be moved over the club handle H or the device held in one hand and the club handle moved axially back and forth therethrough.

Having thus described my invention, I claim:

1. A device for wiping the handles of golf clubs or the like by axial passage of the handle therethrough, said device including a substantially rigid tubular member, a flexible sheath thereover having an inwardly projecting annular portion having an inner peripheral wiping edge and a circumferentially contractile element carried thereby adjacent said wiping edge thereof and constituting means for normally contracting said edge to a lesser diameter than that of the club handle.

2. A device for wiping the handles of golf clubs or the like by axial passage of the handle therethrough, said device including a wiper consisting of an annulus having an inner peripheral wiping edge and means carried by the same adjacent said wiping edge for normally contracting said edge to define a circumference of lesser size than the circumference of the club handle and a housing for a plurality of said annular members including longitudinally spaced annular seats within which said members are mounted and maintained against axial movement.

LESTER J. CARLETON.
